DESIGN FOR A BEER BOTTLE

Harry Ennever, Harrington Park, N. J.

Application December 21, 1933, Serial No. 50,177

Term of patent 14 years

To all whom it may concern:

Be it known that I, HARRY ENNEVER, a citizen of the United States, residing at Harrington Park, county of Bergen, and State of New Jersey, have invented a new, original, and ornamental Design for a Beer Bottle, of which the following is a specification, reference being had to the accompanying drawing, forming part thereof.

Fig. 1 is a full face front elevation of the article, showing my new design.

Fig. 2 is a corner-on front view.

Fig. 3 is a top plan view.

Fig. 4 is a cross-sectional view as on line 4—4 of Fig. 1.

I claim:

The ornamental design for a beer bottle, substantially as shown.

HARRY ENNEVER.
